UNITED STATES PATENT OFFICE.

EMIL CARL ZIMMERMAN, OF NEW YORK, N. Y., ASSIGNOR TO Q & C COMPANY, OF NEW YORK, N. Y., A CORPORATION OF MAINE.

GUARD-RAIL CLAMP.

1,306,988.

Specification of Letters Patent. Patented June 17, 1919.

Application filed March 4, 1918. Serial No. 220,118.

To all whom it may concern:

Be it known that I, EMIL C. ZIMMERMAN, a citizen of the United States, residing at 1833 Marmion avenue, in the county of New York and State of New York, have invented new and useful Improvements in Guard-Rail Clamps, of which, the following is a specification:

This invention relates to improvements in guard rail clamps and consists of a novel arrangement and construction of the parts thereof designed particularly to permit of their being readily and securely placed in position of use and adapted to be retained in effective position independent of the securing means. The device of my invention is furthermore designed to possess other features of advantage over the clamps as heretofore made and to be of very substantial construction so as successfully to resist the thrusts and pounding of heavy traffic without danger of displacement from its effective position.

To this end, valuable features of my present invention consist in the arrangement and correlation of the parts whereby when assembled in position they will be self sustained in effective position with the yoke member thereof properly supported to resist the strains irrespective of whether the clamp is fully tightened up or not. This arrangement not only maintains the effectiveness of the clamp but materially contributes to the simplicity of the tightening operation for it is not necessary to manually support the yoke member during the tightening operation. A further important feature thereof consists of an improved and simplified means for securing the parts in position.

The described and other features and advantages of my present invention are shown in the accompanying drawings wherein like reference characters are applied to the corresponding parts in the several views.

In the drawing Figure 1 is a perspective view showing a desirable embodiment of my invention, illustrating its use in clamping the guard rail in position. Fig. 2 is a vertical

sectional view thereof and Fig. 3, is a plan view thereof with the rails omitted. Fig. 4 is a vertical sectional view of a suitable modified form thereof and Fig. 5, is a plan view thereof.

Referring to the preferred embodiment of my invention as illustrated herein, the numeral 1 designates the usual track rail to which the guard rail 2 is attached by means of the clamping yoke member 3. To co-act with the yoke in the clamping of the rail and to space the respective rails from each other the proper distances a suitable spacer or filler block 4—5 is provided to be interposed between the rails. As shown this spacer block is composed of the two parts 4 and 5 which are separated in a vertical plane on a diagonal line. The adjacent and contacting surfaces of the parts forming the block are desirably formed with vertical corrugations or ribs 6 and grooves 7 adapted to register so as to prevent relative longitudinal movement and to permit of the parts 4 and 5 being assembled to adjust the width of the block for differently spacing the rails. Means are also provided to maintain the block members 4 and 5 against vertical displacement which here consists of an outwardly extending longitudinal rib 8, formed on the block member 4 and extending the entire length thereof and arranged to register and fit within a complementary groove 9 formed on the opposite member 5. As illustrated the member 4 is so formed that it bears over a substantial area upon the upper surface of the rail flange and also engages with the rail on the under side of the head and similarly the member 5 engages with the track rail at widely separated points thereby contributing to the rigidity of the arrangement. The member 4 is also considerably longer than the member 5 to provide a relatively large range of adjustment for spacing of the rails.

An important feature of my present invention consists in the means employed for co-acting with the yoke 3 to clamp the guard rail in position. This is accomplished

without attaching of the yoke to either of the rails and consists of a wedge member 10 of longitudinally tapering form adapted to be interposed between one end of the 5 yoke 3 and one of the rails. In the arrangement illustrated in Figs. 1 to 3, similarly positioned between the opposite end of the yoke and the other of the rails, a spacer block or shoe 11 is arranged. This 10 shoe 11 is formed as shown to bear upon the under side of the rail head and upon the rail base and is also provided with a socket 12 adapted to receive the tapered nose portion 13 of the yoke whereby the 15 shoe 11 is held from longitudinal displacement.

As shown the tapered outer surface 15 of the wedge 10 bears against a flat vertical bearing surface on the inner end of the 20 yoke 3 and the wedge is also formed to bear upon the under side of the rail head as shown and upon the upper surface of the rail base.

A valuable feature of my structure consists in providing means to maintain the 25 proper vertical alignment of the yoke so that it is not permitted to drop down at either end upon loosening of the wedge. This is accomplished by providing the 30 wedge member 10 with an extended bearing flange or ledge 18 arranged as shown to underlie the end of the yoke and provide a support therefor. Similarly the spacer 35 block or shoe 11 is provided with an extending flange 19 underlying the opposite end of the yoke. As will be readily understood by so providing, upon assembling of the parts preparatory to tightening the clamp, the yoke will be properly positioned and the 40 clamping is effected by driving in of the wedge. This operation is thus simplified over types heretofore used wherein it has been necessary to hold the yoke in proper position during the tightening.

45 As indicated best in Fig. 3 the ledge portion 18 of the wedge is provided with a longitudinally arranged series of apertures 21 adapted to receive a securing cotter pin 20 when the wedge has been tightened. This 50 provides a simple and reliable securing means for retaining the parts in position.

The arrangement as shown in Figs. 1 and 3, by reason of the employment of the 55 spacer shoe 11, permits of the parts being assembled without removing the guard rail and also permits of employing the same yoke members with wedge blocks and spacer 60 shoes of varying sizes adapted for different rail sections.

65 While I have shown in Figs. 1 to 3 a preferred embodiment of my invention it will be understood that many modifications thereof can be made without departing from the scope thereof. For instance, in Figs. 4

in the spacing shoes are dispensed with and the yoke at one end is extended inwardly and is formed at its end 22 to have direct bearing engagement with the rail. In this modified form the spacer block 4-5 is formed 70 with the corrugations 6 formed on the edge surface of the rib portion 8 whereby the latter operates to secure the block against both vertical and longitudinal displacement.

At 23, downwardly extending lugs are 75 shown formed on one of the spacer block members and arranged to engage with the yoke on each side thereof so that the spacer block is secured against longitudinal movement.

80 Having described my invention I claim,

1. A rail clamp comprising a clamp bar or yoke member having inwardly directed end portions, a wedge member formed with a rail engaging portion and an inclined 85 wedging surface adapted to be interposed between one end of the yoke and the rail, said wedge member being formed at its base with a ledge flange outwardly extending to underlie the end portion of the yoke 90 member and provide a bearing therefor and said ledge being provided with a series of longitudinally disposed apertures and shiftable securing means adapted to be positioned in said apertures and to engage with 95 the yoke member at points both above and below the base of the rail.

2. The combination of a track rail and a guard rail, of a rail clamp comprising a clamp bar or yoke having upturned and inwardly directed end portions, a wedge formed with a rail engaging portion and an inclined wedging surface adapted to be interposed between one end portion of the yoke and a rail, a bearing shoe member 100 formed with a rail engaging part and adapted to be interposed between the opposite end portion of the yoke and a second rail and an adjustable spacer block adapted to be interposed between the rails, said wedge being 105 formed at its base portion with a flange extension arranged to underlie the end portion of the yoke and formed with a series of apertures arranged longitudinally thereof and a shiftable cotter pin fitted to one 110 of the apertures to engage the yoke member both above and below the base of the rail.

3. A rail clamp comprising a clamp yoke member having upturned inwardly directed 115 end portions forming a space or slot between said end portions and the lower body portion of the yoke member, a wedge member formed with a rail engaging portion and an inclined wedging surface and adapted to be interposed between one end of the yoke and a rail, said wedge member being 120 formed at its base portion with an outwardly extending flange or ledge adapted to be received within the groove formed by 125 130

the yoke member and to underlie the end portion thereof, said ledge being provided with a series of longitudinally arranged apertures, shiftable securing means adapted 5 to be positioned in said apertures and to engage with both the body portion and the

inwardly directed end portion of the yoke to prevent displacement of the wedge, substantially as described.

In testimony whereof I have signed my 10 name to this specification.

EMIL CARL ZIMMERMAN.
